REFLECTOR ADJUSTING MECHANISM FOR PROJECTION LAMPS

Original Filed July 5, 1938

UNITED STATES PATENT OFFICE

2,242,388

REFLECTOR ADJUSTING MECHANISM FOR
PROJECTION LAMPS

Karl Brenkert, Detroit, Mich., assignor to Brenkert Light Projection Company, Detroit, Mich., a corporation of Michigan

Original application July 5, 1938, Serial No. 217,385. Divided and this application January 21, 1939, Serial No. 252,147

5 Claims. (Cl. 240—44.1)

This application is a division of my co-pending application Serial No. 217,385 filed July 5, 1938. The invention pertains to improvements in projection lamps of the carbon electrode type.

The principal object of the invention is to provide a more suitable arrangement of the mechanism for adjusting the reflector. The reflector is capable of independent adjustments on two diametrical axes and of bodily movements lengthwise of the housing. According to the invention, the three operating members for these three movements are positioned at the front wall of the housing. This arrangement permits the operator, while making the adjustments, to stand close to the projection booth porthole, which is the most suitable position for him to take while adjusting the reflector. In previous lamps, the operating members are scattered over the housing, requiring the operator to reach and feel for them or to stand away from the porthole, where the illumination in the booth interferes with his vision of the light projected on the screen.

Another novel characteristic of the arrangement herein described is that the reflector adjusting mechanism, except for the operating members, is disposed entirely behind the reflector. In this position, the mechanism is out of the path of the smoke from the arc and leaves a clear space above the arc for ventilation.

The invention is fully disclosed by way of example in the following description and in the accompanying drawing, in which:

Figure 1 is an elevation, partly in section, of the reflector adjusting mechanism;

Figure 2 is a section on the line 2—2 of Figure 1;

Figure 3 is a plan view, partly in section;

Figure 4 is a section on the line 4—4 of Figure 1;

Figure 5 is a detail section, and

Figure 6 is a detail of Figure 2, partly in section.

Reference to these views will now be made by use of like characters that are employed to designate corresponding parts throughout.

In Figures 1, 2, and 4, the numerals 2 and 3 designate respectively the front and rear walls of a projection lamp housing which may be of conventional design or as shown in the above-mentioned co-pending application. The reflector behind the arc of the lamp is mounted in a circular frame 70 having a bracket 71 formed on the rear side thereof. To the bracket is pivotally attached, on a horizontal axis, an inverted yoke 72 having an upwardly extending stem 72', as

shown more clearly in Figure 6. On the stem is rotatably mounted a cross member 73 having its ends slidably mounted on a pair of horizontal guide rods 74 and 74' suitably mounted in the lamp housing and lengthwise thereof. The ends of the member 73 are formed with sleeves or journals 75 and 75' respectively receiving the guide rods as shown more clearly in Figures 2 and 3. To the rear end of one of the journals 10 is fixed a gear box 76 for purpose that will presently be described. To the adjacent journal is secured a plate 77 through which certain adjustments of the reflector are made, as will presently appear. An arm 78 is formed on the yoke 72, extending laterally therefrom to a point slightly in front of the lower end of plate 77, as shown more clearly in Figures 1 and 2.

Three adjustment rods 79, 80 and 81 are mounted longitudinally in the top of the lamp housing with their forward ends journaled in the front wall 2 of the housing. The rods 79 and 81 extend into the gear box 76 where they carry long pinions 82 and 83 respectively. The rear end of the rod 80 is formed as a screw 84 threaded in the plate 77.

In the forward wall of the gear box 76 are slidably journaled a pair of stub shafts 85 and 86 carrying pinions 87 and 88 respectively meshing with the long pinions 82 and 83 respectively. The shaft 85 is threaded at 89 through the plate 77 and has its forward end in engagement with a lug 90 extending upwardly from the top of the frame 70. The shaft 86 is threaded at 91 through the plate 77 and has its forward end in engagement with the outer end of the lateral arm 78.

The rods 79, 80 and 81 are equipped at their forward ends with turning knobs 92 forward of the front wall 2. Turning the rod 79 rotates pinions 82 and 87 and shaft 85 which, while turning, moves axially by reason of its threaded engagement at 89 with the plate 77. In moving forward, the shaft 85 pushes against the lug 90 and tilts the reflector frame forwardly on the horizontal axis 93 of the yoke 72.

Turning the rod 80 causes the screw 84 to move the plate 77 forwardly or rearwardly. Since this plate is fixed to one of the journals 75 of the cross member 73, the latter is moved lengthwise on the guide rods 74, carrying with it the reflector frame for bodily adjustment forward or rearward without tilting. The plate 77 carries along with it the attached journal 75 and gear box 76. This movement is permitted by the clearance of the guide rod 74 in the journal 75 formed 45 on the gear box.

Turning the rod 81 rotates the pinions 83 and 88 and the shaft 86. The latter threads through the plate 77 at 91 and bears against the lateral arm 78 to turn the reflector on its vertical axis or stem 72'. The shifting of both threaded shafts 85 and 86 is permitted by the engagement of their pinions 87 and 88 with the long pinions 82 and 83. A spring 94 extending from one of the journals 75 to the frame 70 maintains the members 78 and 90 in contact with the shafts 86 and 85 and determines the position of the reflector frame when these shafts are retracted.

It may now be seen that all three necessary adjustments of the reflector are made from operating members located at the front wall of the lamp housing. This arrangement permits the operator to be close to the projection booth porthole in making adjustments. Hitherto, at least one of the adjustment handles has been placed at the rear part of the lamp housing in a position compelling the operator to stand at some distance from the porthole, in which position his vision is affected by the light in the booth while making an adjustment, with the result that the adjustment is not accurately made.

Another advantage of the construction described herein is that the operating mechanism is behind the reflector where it is not in the path of the smoke of the arc and does not interfere with the ventilation of the arc.

Although a specific embodiment of the invention has been illustrated and described, it will be understood that various alterations in the details of construction may be made without departing from the scope of the invention, as indicated by the appended claims.

What I claim is:

1. In a projection apparatus, a housing, guide means mounted lengthwise in said housing, a supporting member slidably mounted on said means, a reflector support pivotally carried by said member, a reflector frame pivotally carried by said support on an axis perpendicular to the pivotal axis of said support, means for selectively tilting said support and frame on their respective pivotal axes, means for bodily moving said supporting member on said guide means, said tilting means and said moving means being disposed at the rear side of said frame, and operating members extending from said tilting means and said moving means across the periphery of said frame and through the front wall of said housing.

2. In a projection apparatus, a housing, guide means mounted lengthwise in said housing, a supporting member slidably mounted on said

means, a reflector support pivotally carried by said member, a reflector frame pivotally carried by said support on an axis perpendicular to the pivotal axis of said support, lengthwise movable rods for selectively tilting said support and frame on their respective pivotal axes, pinions on said rods, operating members adjacent to said pinions, elongated pinions on said operating members and meshing respectively with the first named pinions, and means for bodily moving said supporting member on said guide means.

3. In a projection apparatus, a housing, guide means mounted lengthwise in said housing, a supporting member slidably mounted on said means, a reflector support pivotally carried by said member, a reflector frame pivotally carried by said support, screws threaded through said supporting member and respectively engaging said support and frame laterally of their respective pivotal axes, rotatable operating rods extending through the front wall of said housing and geared to said screws, and means for bodily moving said supporting member on said guide means.

4. In a projection apparatus, a housing, guide means mounted lengthwise in said housing, a supporting member slidably mounted on said means, a reflector support pivotally carried by said member, a reflector frame pivotally carried by said support on an axis perpendicular to the pivotal axis of said support, screws engaging said support and frame for selectively tilting them on their respective pivotal axes, pinions on said screws, operating members adjacent to said pinions, pinions on said operating members and meshing respectively with the first named pinions, all said pinions being disposed behind said frame, and means for bodily moving said supporting member on said guide means.

5. In a projection apparatus, a housing, guide means mounted lengthwise of said housing, a supporting member slidably mounted on said guide means, a reflector support pivotally carried by said member, a reflector frame pivotally carried by said support on an axis perpendicular to the pivotal axis of said support, means for propelling said member on said guide and extending through the front wall of said housing, a pair of screws threaded in said member and respectively engaging said support and said frame to turn them on their respective axes, and a pair of rods rotatably mounted in and extending through the front wall of said housing, said rods being geared respectively to said screws for rotating the latter.

KARL BRENKERT.
